(57) **CLAIM**

The ornamental design for convertible smart headphones with speakers and mood sensors, as shown and described.

DESCRIPTION

FIG. 1 is a front perspective view of the invention.

FIG. 2 is a rear perspective view of the invention.

FIG. 3 is a top view of the invention;

FIG. 4 is a bottom view of the invention with both speaker and headphone in use;

FIG. 5 is a right side view of the invention with speaker in use;

FIG. 6 is a left side view of the invention;

FIG. 7 is a front elevation view of the invention; and,

FIG. 8 is a front elevation view of the invention with both a speaker and a headphone in use.

1 Claim, 6 Drawing Sheets
